UNITED STATES PATENT OFFICE.

ELIAS BERNHARD MÖLBACH, OF FREDRIKSSTAD, NORWAY.

CENTRIFUGAL SEPARATOR.

Application filed October 19, 1928, Serial No. 313,597, and in Norway October 29, 1927.

This invention relates broadly to the art of separating by centrifugal force and more particularly to the process of separating in a centrifugal separator of the type where the mass or fluid to be separated is fed to a rotatable drum, containing a stack of conically shaped discs which serve to divide the fluid space of the drum into a number of annular separating compartments.

When operating, the drum containing the fluid and the discs are rotated at a suitable speed, and the separation of the fluid or mass will take place in the annular layer between each pair of discs, the heavier particles due to the centrifugal force, tending to move radially outwards, until they strike the inner surface of the disc on the outside of the layer, whereafter they will follow this surface to the discharge channel, while the lighter particles will occupy the place closer to the centre of rotation and by means of the feeding pressure be forced to enter the proper discharge channel. In some cases the fluid to be separated is during the separation moving from the central towards the peripheral part of the apparatus in other cases, in the opposite direction.

It is furthermore very common to feed the mass through holes in the discs to a so-called "neutral" zone, from which the separation can take place.

One of the objects of this invention is to provide means for feeding the fluid or mass to the "neutral" zone between two adjacent rotating discs, thereby facilitating separation by avoiding eddies in the fluid on account of the feeding.

Another object of this invention is to provide means whereby the separation can take place as the fluid or mass is fed from the annular space surrounding the stack of discs towards the centre of rotation, means being provided, whereby fractions of different specific gravity—as the fluid is forced towards the centre of the stack—will be divided into individual layers and discharged through separate channels.

Still another object of this invention is to provide the centrifugal separators of the type described with intermediate conical discs of smaller diameter than the main discs, arranged between the latter, the arrangement being such that the annular space between main discs and intermediate discs or

between intermediate discs each is in communication with separate feeding or discharge channels which are arranged in communication with the corresponding spaces between any other pair of main discs.

Another object of this invention is to provide a separator of the above type with means for utilizing the kinetic energy of the fractions in order to convey them and also to provide a certain back pressure.

Other objects and advantages of the invention will be apparent from the drawings illustrating preferred embodiments of the invention as examples only in connection with the description below.

In the drawings,

Fig. 1 is a vertical sectional view on the line II—II of Fig. 2, showing a centrifugal separator according to the invention.

Fig. 2 is a horizontal section on the line I—I of Fig. 1, this section being such that the left half of the figure is a section through a main disc and the right half a corresponding section through an intermediate disc, which—when stacked in the separator—will be placed below the first mentioned main disc.

Fig. 3 is a vertical sectional view of a combination of a main disc and an intermediate disc on the line III—III of Fig. 2.

Fig. 4 is a sectional view on the line V—V of Fig. 5, similar to Fig. 1, but of a modified embodiment of the invention.

Fig. 5 is a horizontal section on the line IV—IV of Fig. 4, similar to Fig. 2.

Fig. 6 is a detail.

Fig. 7 is another detail.

Fig. 8 is a sectional view of a third embodiment of the invention, and

Fig. 9 is an end view of Fig. 8.

With reference to Figs. 1—3, the centrifugal separator consists of a base 1, suitable for mounting a vertical shaft 2, provided with suitable driving means, such as a pulley or the like 3, the upper end 4 of the shaft 1 being conically shaped and fitting into a corresponding recess 5, centrally located in the bottom of the separating drum 6. Inside the drum 6, the separating main discs 7 and the intermediate discs 8 are alternately stacked. These discs are shaped in such a manner that when properly arranged, they will form a body, comprising a central opening 9, annular separating spaces 10, 11, 12, vertical

channels 13, communicating with the spaces 11, and radial apertures 14, communicating with the central opening 9.

The diameter of the larger discs 7 is such that an annular vertical space 15 will be left between the circumference of the discs and the side walls of the drum 6.

The stack of discs in the separator is held in place by means of a drum cover 16, secured 10 to the drum by means of a nut 17. Between the cover 16 and the drum 6 suitable packing is provided, serving to make the joint tight. The cover is so constructed that when the nut 17 is drawn up tightly, the upper part 15 of the cover will press against the stack of discs with a sufficient pressure to hold them together. It is further provided with channels and openings in such a manner that the above mentioned channels and openings 20 formed by the discs will be continued through the cover and communicate with collecting chambers 18 and 19, arranged above the cover, from which pipes 20 and 21 lead out into the open.

25 The cover is further provided with a number of openings 22, connecting the annular space between the top of the top disc 7 and the inside conical part of the cover with the collecting compartment 19.

30 The operation of the separator is as follows:

Fluid or mass is fed to the central space 9 from a faucet or the like 23 and passes 35 through the apertures 14 into the space 12 between the upper side of the intermediate discs 8 and the lower side of the discs 7, while the revolving parts of the separator is being rotated.

30 The diameter of the disc 8 is chosen such 40 that when the fluid reaches the edge of these discs, it will enter the separating space 10 at a "neutral" distance from the centre of rotation, the "neutral" zone meaning the zone or stratum which divides theoretically 45 between the heavy and the light particles. The fluid or mass will now be separated into two fractions, the heavier one moving out towards the circumference of the discs and passing into the annular space 15 between 50 the discs and the drum. From here it will continue through the openings 22 in the cover and out into the collecting chamber 19 and will be discharged through the pipe 21, while the lighter fraction will pass in under 55 the discs 8 and be carried through the channels 13 to the collecting chamber 18 and pass out of the pipe 20.

In the drawing, the stack of discs is shown 60 built up of units, each consisting of one main disc 7 and a small disc 8 including the necessary spacing collars, all made in one piece. This, of course, is not necessary, as the stack of discs may also be built up of a number of 65 separate large and small discs with individual spacers between.

The embodiment illustrated in Figs. 4, 5, 6 and 7 differs from that just described mainly therein that the fluid or mass to be treated is passing inwardly during the centrifugal separating action. In this case the discs 8' 70 and 7' are stacked on a central hollow pipe-like member or core 25.

Between the flange 27 formed on the lower end of the core 25 and the bottom of the drum 6 an opening 28 is formed.

75 The individual discs 7' and 8' are provided with a number of holes 29, arranged at a distance from the centre and a central hole 30 (Fig. 5), the latter one having such a diameter that it will fit snugly over the so pipe 25.

When stacking the discs, one or more of the discs 8' is placed between each pair of main discs 7' in such a manner that the holes 29 will align to form vertical channels 31 and 32. A star shaped spacer 33 (Fig. 6) provided with holes 34 and a central hole 35 which will fit over the pipe 25 is placed between each pair of discs and is arranged in such a way that one of the said channels 31 90 and 32 alternately will go through one of the holes 34 and be open to the space between adjacent discs, thereby constituting individual channels, communicating with corresponding spaces between each pair of main 95 discs 7'.

If more than one intermediate disc 8' is used between each pair of main discs 7' (say for instance two), then another type of spacer 33' as shown in Fig. 7 may be used, whereby three separate groups of channels will be formed, each group communicating with corresponding spaces between each pair of main discs 7'.

The distances from the centre to the said 105 channels can be different.

This separator will work in the following manner:

While the separator is being rotated at a suitable speed, fluid or mass is fed from the faucet and will pass through the central hole 36 and follow the bottom of the drum 6 radially in all directions. Due to the force of gravity, the centrifugal force or/and artificial pressure available in the feed-line the 110 fluid will be forced to pass up along the vertical inside walls of the drum and further towards the centre of rotation of the discs.

The separation of the fluid will take place 115 between the main discs, while it is forced towards the centre of rotation, the heavier particles will tend to follow the inside of the discs 7' and the lighter ones will occupy the space further away from the discs. As the fluid reaches the edge of the disc or discs 8', it will be divided up into two or more 120 different layers of different gravity, each layer being carried away through corresponding groups of channels 31 and 32; the heavier fraction will go through the chan- 125 130

nels 31 and the lighter ones through the channel 32.

When more than one intermediate disc 8' is used, the fluid will be divided up into a greater number of fractions of different gravity.

In Figs. 8 and 9 is shown a horizontal separator, where the principle of separation described in connection with Figs. 1, 2 and 3 is applied in combination with a system to some extent already known for utilizing the kinetic energy of the fractions and to establish a back pressure which will tend to force the lighter fraction against the centrifugal force towards the centre of rotation. The principle described below can also—with suitable modifications—be applied to the two forms of separator already described.

The separator here consists of a bedplate 37, whereon are mounted uprights 38 and 39, including bearings 40 and 41 and a stator 44. The shaft 42 projects through the stator, is carried in the said bearings and is in one end furnished with a coupling, unit or the like 43, suitable to connect the shaft to some driving means, not shown.

The openings in the stator 44, through which the shaft extends, are closed by means of bushings 45 and 46. On the right hand side of the stator an annular feeding chamber 47 is arranged in connection with the feed pipe 48. Surrounding the middle part of the stator is a spiral pump house 49, which communicates with the discharge pipe 50. On the left hand side of the stator another spiral pump house 51 is arranged, communicating with a discharge pipe 52.

The rotor consists of a casing or drum 53, keyed to the shaft 42, and provided with feeding channels 54 and discharge channels 55, the first ones in connection with the feeding chamber 47 and the latter communicating with the pump house 51 by means of an annular chamber 56. In the circumference of the last mentioned chamber 56, a number of pump blades 57 are fastened to the rotor. These serve to aid the pump action and to establish a suction which will aid the lighter fraction in its way towards the centre of rotation, as will later on be described. Similar blades 58 are arranged in that part of the rotor casing which terminates in the pump house 49, located in the middle section of the stator and serve to aid the pump action of the heavier fraction.

Main and intermediate separating discs 59 and 60 are alternately arranged on the shaft 42 inside the casing 53, in such a manner that they will rotate with the shaft. These discs—as explained in connection with Figs. 4, 5 and 6—are provided with holes in such a manner that when assembled, two groups of channels will be formed, the first group communicating with the feeding channels 54 and with all the spaces between the right hand side of the

intermediate discs 60 and the adjacent main discs 59, and the other group with the discharge channels 55, leading eventually to the discharge pipe 52 through the annular chamber 56 and the pump house 51, and the spaces between the left hand side of the intermediate discs 60 and the adjacent main discs 59.

Inlet and discharge pipes 63, 64 and 65 are further provided in connection with the stator, which serve to furnish water, air, etc. to the space between the rotor and the stator casings 53 and 54, when desired.

The operation of this separator is as follows:

The fluid to be separated is fed through the pipe 48, chamber 47, channels 54 and 61 and will pass out at the right hand side of the discs 60 and enter the separating space between two discs 59 at a suitable "neutral" distance from the centre of rotation. The heavier fraction will pass radially outwards along the inside of the discs 59 and be aided in their way to the pump house casing and further out into the discharge pipe 50 by means of the pump blades 58.

The back pressure established will tend to aid the movement of the lighter fraction towards the centre of rotation and in under the intermediate discs 60, and this fraction will pass through the channels 62 and 55 and the annular chambers 56 to the pump house casing 51. The rotating blades 57, arranged in the circumference of the chamber 56, will tend to aid the lighter fraction to enter the pump housing and further pass out through the discharge pipe 52.

In order to regulate the density of each of the fractions, choke valves—not shown—may be arranged in one or both of the discharge pipes.

This invention is not limited to the details of construction described, said description only serving to make the invention more clearly understood, as many changes can be made in the details of construction and in the arrangement of the individual parts.

Claims:—

1. A centrifugal separator, comprising a rotatable drum, driving means for said drum, a cover for said drum having feeding and discharge openings, a plurality of conically shaped main separating discs in said drum forming narrow annular separating spaces, said discs having apertures forming channels for feeding the mass or fluid from the feeding hole in said drum to the space between each pair of discs, and means whereby said mass or fluid is guided radially outwards to a "neutral" zone in the space between each pair of said discs, said means comprising intermediate discs of smaller diameter than the above mentioned discs, the space on the side of each intermediate disc and the adjacent main disc between each pair of main discs forming part of said feeding channels to the separating

space, and said main discs having apertures and intermediate discs forming discharge channels communicating with each space on the corresponding side of said intermediate discs and said main discs.

2. A centrifugal separator, comprising a rotatable drum, driving means for said drum, a cover for said drum having feeding and discharge openings, a feeding pipe extending from said cover into said drum, a flange on the lower end of said pipe, main separating discs stacked on said pipe, intermediate discs of smaller diameter than said main discs stacked on said pipe between said main discs, spacers stacked on said pipe between each of said discs, apertures in said discs, and said spacers, forming channels substantially parallel to the axis of rotation and cut-away portions on said spacers connecting corresponding spaces between the individual discs between each pair of main discs to corresponding channels substantially parallel to the axis of rotation.

3. A centrifugal separator, comprising a rotatable drum, a stator surrounding said drum and having feeding- and discharge openings, a plurality of conically shaped main separating discs in said drum, forming narrow annular separating spaces, said discs having apertures therein forming channels for feeding the mass or fluid from the feeding hole in said drum to the space between each pair of discs, and means whereby said mass or fluid is guided radially outwards to a "neutral" zone in the space between each pair of said discs, said means comprising intermediate discs of smaller diameter than the above mentioned discs, the space on the side of each intermediate disc and the adjacent main disc between each pair of main discs forming part of said feeding channels to the separating space, said main discs and intermediate discs having apertures therein forming discharge channels, communicating with each space on the corresponding side of said intermediate discs and said main discs between each pair of main discs, said separating spaces at the circumference communicating with annular spaces around said stator and said drum, comprising paddle-blades in its circumference to aid the heavier fraction to enter the annular spaces, whereby a pump action is secured which establishes a back pressure to aid the lighted fraction to move towards the centre of rotation.

4. A centrifugal separator, comprising a rotatable drum having feeding- and discharge openings therein, a plurality of conically

shaped main separating discs in said drum, forming narrow annular separating spaces, 60 said discs having apertures forming channels for feeding the mass or fluid from the feeding hole in said drum to the space between each pair of discs, and means whereby said mass or fluid is guided radially outwards to a "neutral" 65 zone in the space between each pair of said discs, said means comprising intermediate discs of smaller diameter than the above mentioned discs, the space on the side of each intermediate disc and the adjacent main disc 70 between each pair of main discs forming part of said feeding channels to the separating space, said main discs and intermediate discs having apertures therein forming discharge channels, communicating with each space on 75 the corresponding side of said intermediate discs and said main discs between each pair of main discs, a centrifugal pump communicating with said discharge channels and comprising pump-blades in its circumference to 80 aid the lighter fraction in its movement towards the centre of rotation and the heavier fractions to be raised to a level above the head of the feeding line.

5. A centrifugal separator, comprising a 85 rotatable drum, driving means for said drum, a cover for said drum having feeding and discharge openings, a plurality of conically shaped main separating discs in said drum providing narrow annular separating spaces, 90 conically shaped intermediate separating discs of smaller outside diameter between each pair of said main separating discs, dividing the inner portion of each of said annular separating spaces into a plurality of annular 95 passages outwardly communicating with the outer portion of said narrow annular separating spaces between each pair of main discs, spacers between said main and said intermediate discs, a central axial channel in the 100 drum, said channel and said spacers having radial apertures therein and said discs having axial apertures forming a plurality of annularly disposed channels around said central channel, one of the said passages between each 105 pair of main discs inwardly communicating with said central axial channel through said radial apertures, and the remainder of said passages between each pair of main discs 110 communicating with separate groups of said annularly disposed channels around said central channel, substantially as and for the purposes set forth.

In testimony whereof I have signed my name to this specification.

ELIAS BERNHARD MÖLBACH.
